Primary Examiner — Cathron C Brooks*Assistant Examiner* — Sharon S Oum(74) *Attorney, Agent, or Firm* — Pai Patent & Trademark Law Firm; Chao-Chang David Pai(57) **CLAIM**

The ornamental design for a ceiling fan blade mounting ring, as shown and described.

DESCRIPTION

FIG. 1 is a front top perspective view of a ceiling fan blade mounting ring showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front bottom perspective view thereof.

The broken lines illustrate portions of the ceiling fan blade mounting ring that form no part of the claimed design.
